DESIGN FOR A THREAD DISPENSER OR THE LIKE

Clifford Brooks Stevens, Milwaukee, Wis., assign-
or to The S & W Hydraulic Tool Company,
Wynne, Ark., a corporation of Arkansas

Application September 28, 1942, Serial No. 108,348

Term of patent 14 years

To all whom it may concern:

Be it known that I, Clifford Brooks Stevens, a citizen of the United States, residing in the city of Milwaukee, county of Milwaukee, State of Wisconsin, have invented a new, original, and ornamental Design for a Thread Dispenser or the like, of which the following is a specification, reference being had to the accompanying drawing, forming a part thereof.

Figure 1 is a perspective view of a thread dispenser or the like showing my new design.

Figure 2 is a top plan view thereof.
Figure 3 is a bottom view thereof.
Figure 4 is a side elevational view thereof.
The dominant features of my new design are shown in full lines.

I claim:
The ornamental design for a thread dispenser or the like, as shown and described.

CLIFFORD BROOKS STEVENS.
